TABLET ARMCHAIR

Severin B. Hendrickson, Templeton, Mass., assignor to Heywood-Wakefield Company, Gardner, Mass., a corporation of Massachusetts

Application February 28, 1955, Serial No. 34,775

Term of patent 7 years

(Cl. D15—1)

Fig. 1 is a front perspective view of a tablet armchair showing my new design;

Fig. 2 is a rear elevation thereof on a scale reduced with respect to that of Fig. 1; and

Fig. 3 is a top plan view on a slightly smaller scale than Fig. 1.

I claim:

The ornamental design for a tablet armchair, substantially as shown.
